SYSTEM FOR REPRODUCING SOUNDS FROM DISTORTED SOUND RECORDS.

Application filed November 19, 1927. Serial No. 234,498.

It is well known that in the electrical transmission of sounds or music, either through wires or wirelessly, certain difficulties arise due to the fact that tones of low frequencies, which impart to the human ear impressions of the same power as impressions imparted to the ear by tones of high frequencies, have amplitudes which are several times greater than the amplitudes of the said tones of high frequencies.

If sound and music were transmitted without distortion, the fact referred to above would necessitate that the dimensions of the transmission means in question—for instance, the amplifiers, wireless transmitters etc.—having essentially the same sensitivity to higher and lower frequencies, be determined by the powerful influence of tones of low frequencies, in which case the transmission means would be very expensive. Furthermore, when recording phonograms the low frequencies would dominate the mean and high frequencies, so that when the low frequencies would attain the maximum amplitude available the mean and the high frequencies would be so very diminutive in the phonogram that the size of the grains in the sensitizing emulsion on the film and of the unavoidable defects in the film itself might be considerably relatively to the last-named variations and, consequently, cause distortions in the reproduction of the sounds.

In order to avoid these difficulties, we have attempted to weaken by artificial means the amplitudes of low frequencies during the recording in such a way that sound variations with one and the same intensity of sound to the human ear independently of their frequency will produce current variations of practically one and the same amplitude; and to annihilate this weakening during the reproducing by using a member which has a greater sensitiveness to the low frequencies than to the high frequencies.

Now, we have found that this compensation may be effected to a certain degree by using a loud speaker with a loosely suspended or floating diaphragm, such loud speakers

having the characteristic property of preferring the very low frequencies. However, it has been found that the compensation which may be obtained in this way is, in the first place, insufficient and, in the second place, does not allow any fine regulation of the proportion between the low and high frequencies which may be necessary in order to obtain a complete compensation.

To overcome these difficulties, we utilize the well-known phenomenon that the sensitivity of a selenium cell increases when the frequency of the light variations influencing the cell decreases.

The reproducing system includes in well-known manner an inductance and an ohmic resistance, which are interconnected in series and are connected across the grid circuit of a thermionic tube, in the grid circuit of which a selenium cell is inserted. According to the invention, the value of the resistance is determined in relation to the value of the inductance in the reproducing system and of the capacity and the ohmic resistance in the recording system as referred to hereinafter.

A more thorough understanding of our invention may be had from the following detailed description taken in connection with the accompanying drawing, in which:

Figure 1 illustrates an ordinary sound recording system, wherein the sound amplitudes of low frequencies are weakened during the recording; Fig. 2 illustrates a sound reproducing system and Fig. 3 is a diagram illustrating the distortion caused during the recording and the counter-distortion caused during the reproducing.

The sounds to be recorded on a film *f* are caused to influence a transmitter, preferably a condenser microphone *c*, Fig. 1, which is inserted in circuit with the grid *g* of a thermionic tube *t*, such circuit also containing a battery *b*, a resistance *R*, a grid resistance *y* and a blocking condenser *k*. Now, by choosing the value of the resistance *R* properly in relation to the capacity of the condenser microphone *c*, it is possible to obtain that sound variations with one and the same intensity of sound to the human ear inde-

pendently of their frequency will produce current variations of practically one and the same amplitude in the anode circuit a of the tube t , wherefore a registering device, for instance an oscillograph m , which is influenced by said current variations and reflects a beam of light from a light source l towards the film f , will record a distorted phonogram p on the latter.

- 10 If the condenser microphone c is influenced by a sound variation with the frequency $\omega = 2\pi.n$, then the said condenser will act as a generator. If the electromotive force thereof is E , and the generator, i. e., the microphone c , is coupled to a resistance R (Fig. 1) having a small value relatively to the grid resistance y , then the voltage variation superimposed on the grid is expressed by

$$20 \quad \Delta e = \frac{E \cdot \frac{R}{C}}{\sqrt{R^2 + \left(\frac{1}{C\omega}\right)^2}} = \frac{E \cdot \frac{1}{y}}{\sqrt{1 + \frac{1}{(R\omega C)^2}}}$$

where C is the capacity of the condenser microphone c .

- 25 The distortion d of the sound amplitudes in the phonogram p or, more exactly, of the current variations caused in the anode circuit a of the recording system, varies in harmony with the expression

$$\frac{1}{\sqrt{1 + \frac{1}{(R\omega C)^2}}}$$

- 35 and is illustrated by the curve I in Fig. 3.

If, in the reproducing system illustrated in Fig. 2, the film f is moved longitudinally and light is passed through the film and concentrated on a selenium cell s , by means of a lens i , which forms on the cell an image of the phonogram p , then the electrical conductivity of the selenium cell s will vary, and these variations are proportional to the amplitudes in the phonogram p and at the same time inversely proportional to the frequencies of the light variations.

40 If the selenium cell s is inserted in the grid circuit of a thermionic tube t , and an inductance L is connected across said circuit, then the inductance L will compensate the distortion, which the well known sluggishness of the selenium cell causes in the current amplitudes of the reproducing system.

45 Now the phonogram p is a distorted sound record and, therefore, a sound reproducer, for instance a loud speaker h , in the anode circuit A of the tube T would reproduce distorted sounds unless the distortion caused during the recording of the sound is annihilated by a corresponding counter-distortion in the reproducing system.

50 According to the present invention, such a counter-distortion is caused partly by the use of a loud speaker of the floating-diaphragm type and partly by the insertion

of an ohmic resistance r in series with the inductance L . The said resistance r will prevent, by the low frequencies, the distortion, which is due to the sluggishness of the selenium cell, from being compensated by the inductance L and, therefore, will influence the current amplitudes in the reproducing circuits; and if the resistance r is properly determined, it is possible to obtain a complete compensation of the distortion introduced in recording.

55 If, for a moment, we neglect the compensating effect which may be obtained by using a loud speaker with floating diaphragm, we can show that a complete counter-distortion may be effected by properly determining the resistance r .

60 If the variation caused in the voltage across the selenium cell s by the illumination of the same, is E' , then said voltage variation is expressed by

$$E' = \frac{K}{\omega}$$

65 where K is a value which varies proportionately to the amplitudes in the phonogram.

If the grid resistance x of the tube T is large relatively to the impedance of the inductance L and of the resistance r , then the voltage variation superimposed on the grid of the tube T is

$$\Delta e' = E' \sqrt{(L\omega)^2 + r^2}$$

$$\sqrt{(L\omega)^2 + (r + \rho)^2}$$

70 where ρ is the ohmic resistance of the selenium cell s . If

$$\sqrt{(L\omega)^2 + r^2}$$

75 by the highest value of the frequency ω is small relatively to ρ , then the expression for $\Delta e'$ may be reduced to

$$80 \quad \Delta e' = E' \cdot \frac{\sqrt{(L\omega)^2 + r^2}}{r}$$

85 or by the insertion of $\frac{K}{\omega}$ for E' to:

$$90 \quad \Delta e' = \frac{K \cdot L}{\rho} \cdot \frac{1}{\sqrt{1 + \left(\frac{r}{L\omega}\right)^2}}$$

95 The amplitudes of the reproduced sounds vary proportionately to $\Delta e'$, and because $\Delta e'$ depends upon the frequency and increases when the frequency decreases, the reproduced sounds are distorted in comparison with the distorted sound amplitudes in the phonogram. The said distortion caused in the reproducing system is illustrated by the curve II in Fig. 3, from which it is evident that the distortion in the recording system is counteracted by the distortion in the reproducing system.

130

The first distortion, expressed by the value:

$$\frac{1}{\sqrt{1 + \frac{1}{(R \cdot C\omega)^2}}}$$

5 (see above) will be annihilated by the second distortion expressed by the value:

$$\sqrt{1 + \left(\frac{r}{L\omega}\right)^2}$$

10 if

$$\sqrt{1 + \left(\frac{r}{L\omega}\right)^2} = \sqrt{1 + \frac{1}{(R \cdot C\omega)^2}}$$

15 or consequently if

$$\frac{r}{L} = \frac{1}{R \cdot C} \text{ or } r = \frac{L}{R \cdot C}$$

20 From this formula, it is evident that the distortion of the low frequencies during the recording may be entirely compensated in the reproducing system by proper selection of the value of the ohmic resistance r .

25 We claim as our invention:

1. A system for reproducing sounds from phonograms, the amplitudes of which are distorted relatively to the amplitudes of the original sounds during their previous conversion into current variations in such a way that the lower frequencies are suppressed in relation to the higher frequencies: such reproducing system comprising a selenium cell adapted to be illuminated by light passing through the phonogram; an inductance; a source of current; a current circuit wherein said cell, inductance and current source are included in series; a thermionic tube having a grid circuit and a plate circuit, the grid circuit being connected across the inductance and the resistance in series; and a sound producer inserted in the plate circuit; the said resistance having the value

$$r = \frac{L}{R \cdot C}$$

70 where L is the value of the inductance in the reproducing system, and R and C the values of the ohmic resistance and the capacity, respectively, in the recording system.

In testimony whereof we affix our signatures.

ARNOLD POULSEN.

AXEL CARL GEORG PETERSEN.

40 circuit, the grid circuit being connected across the inductance; a sound reproducer inserted in the plate circuit; and means for annihilating in the voltage variations superimposed upon the grid the distortions caused during recording.

45 2. A system for reproducing sounds from phonograms, the amplitudes of which are distorted relatively to the amplitudes of the original sounds during their previous conversion into current variations in a circuit which includes a capacity, an ohmic resistance, a thermionic tube having a grid circuit across which the resistance is connected and a plate circuit, and a sound recorder inserted in the plate circuit: such reproducing system comprising a selenium cell adapted to be illuminated by light passing through the phonogram; an inductance; a resistance; a source of current; a current circuit wherein said cell, inductance, resistance and current source are included in series; a thermionic tube having a grid circuit and a plate circuit, the grid circuit being connected across the inductance and the resistance in series; and a sound producer inserted in the 60 plate circuit; the said resistance having the value

$$r = \frac{L}{R \cdot C}$$

65

70 where L is the value of the inductance in the reproducing system, and R and C the values of the ohmic resistance and the capacity, respectively, in the recording system.
